(57) **CLAIM**

The ornamental design for the “apparatus for gas delivery”, as shown and described.

DESCRIPTION

FIG. 1 is a perspective view of an apparatus for gas delivery showing my new design;

FIG. 2 is a plan view thereof, taken from above;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a plan view thereof, taken from below.
